(57) **CLAIM**

The ornamental design for a headset speaker, as shown and described.

DESCRIPTION

FIG. 1 is a top, front, right-side perspective view of a headset speaker. The design includes a mirror image of the embodiment depicted;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof;

FIG. 8 is top, front, right-side perspective view thereof including a disclaimed headset for environmental context;

FIG. 9 is front view thereof;

FIG. 10 is a back view thereof;

FIG. 11 is a left-side view thereof;

FIG. 12 is a right-side view thereof;

FIG. 13 is a top view thereof; and,

FIG. 14 is a bottom view thereof.

The broken lines depict portions of the headset speaker and environment of the headset speaker that form no part of the claimed design.

1 Claim, 14 Drawing Sheets

Related U.S. Application Data

division of application No. 29/644,686, filed on Apr. 19, 2018, now Pat. No. Des. 857,692.
